Des. 233,056
Patented Oct. 1, 1974

233,056

ACTION PULL TOY

Walter P. Doe, East Aurora, N.Y., assignor to The Quaker Oats Company, Chicago, Ill.

Filed Dec. 6, 1972, Ser. No. 312,588

Term of patent 14 years

Int. Cl. D21—01

U.S. Cl. D34—15 AD

FIG. 1 is a front perspective view of a pull top showing my new design;

FIG. 2 is a top plan thereof;

FIG. 3 is a rear elevation thereof; and

FIG. 4 is a bottom view thereof.

I claim:

The ornamental design for an action pull toy, substantially as shown.
